PAINTBRUSH

Harry A. Rishel, Ambler, Pa.

Application September 6, 1941, Serial No. 409,793

5 Claims.

(Cl. 15—169)

This invention relates generally to girdles or sleeves for paint brushes, the bristles whereof, it is requisite to vary effectively in length according to the width of surface to be covered.

More specifically the present improvements have reference to what may be conveniently termed a quick acting reciprocatable sleeve for paint brushes of which the bristle pack is preferably preformed oval or its equivalent in shape.

1. The primary object of this invention is to avoid bending or damage to the bristles of the brush when installing the sleeve, and this is accomplished by so constructing the sleeve and the brush that the former may be placed in its working position, initially or after having been removed for cleaning by slipping it over the handle of the brush as a one piece unit.

2. Another object is to provide a girdle of novel construction whereby paint collecting on the inside thereof is prevented from working back to the paint brush handle.

3. A further object is to provide the girdle with a handle or grip to facilitate its instant movement back or forth over the bristles at the will of the user.

4. A still further object is to provide means for preventing paint riding up onto the outside of the girdle as it is pushed down over the bristle pack and ultimately reaching the grip of the sleeve.

5. Another object of this invention is to automatically hold the sleeve in any desired position within its limit of travel.

6. A further object is to provide a temporary reservoir for excess paint on the exterior of the bristle pack, if desired.

7. A still further object is to avoid paint dripping from the bristle pack when the sleeve is pushed over them.

8. An additional object of this invention is to have the sleeve completely free of openings whereby paint works through them with the consequent annoyances.

9. Another object of this invention is to be able to quickly and easily remove the sleeve or girdle from the brush for purposes of cleaning.

The combination of the above improvements provide a most practical working brush, especially for those persons less experienced in painting. The reciprocatable sleeve is so formed that it purposely avoids compressing the bristles. This is most desirable for the bristles, if compressed at the line of emergence from the girdle are unable to absorb paint to the full extent above this line, when dipped for a new supply. For my purpose this is highly objectionable, for when painting the putty strip of a window frame, it requires a very short bristle exposure, if smearing the glass is to be avoided. This would require a frequency

of dipping, which is not only annoying but also slows down the speed of coverage.

Furthermore my invention allows the user to instantly uncover the full length of bristles protruding from the brush ferrule or band in which the bristles are fastened without the necessity of removing the girdle from the brush.

With the stated and other objects in view my invention consists in the novel features of construction, mode of manipulation and combination and arrangement of parts hereinafter fully disclosed, illustrated by the accompanying sheet of explanatory drawings, constituting a part of this specification and particularly pointed out in the claims hereunto appended.

In the drawing:

Fig. I is a side elevational view of a paint brush with its bristles taken along its horizontal axis, and showing in section the quick acting sleeve and its grip in position on its combination ferrule and guide piece. Also, a removable stop pin in place in the handle shank is shown.

Fig. II is an end view of the same.

Fig. III is a side elevational view, similar to Fig. I, but showing in addition thereto a wiper or packing, attached to and encircling the oval shank of the brush handle. A modified form of spring stop fixed permanently to the handle is also shown.

Fig. IV is a sectional view of the same taken on the line IV—IV.

Fig. V is a fragmentary sectional view of a paint brush taken along its horizontal axis and showing in particular a modified form of wiper in accordance with this invention, in which the wiper is attached to the quick acting reciprocatable girdle. Also is illustrated a modified form of spring stop to limit the sleeve travel. This is attached to the sleeve instead of being fastened to the brush handle.

Fig. VI is a sectional view taken on the line VI—VI of Fig. V.

Fig. VII is a view similar to Fig. I but showing in addition thereto a paint guard formed by flaring out the end of the reciprocatable sleeve.

Fig. VIII is a view similar to Fig. I but showing in addition thereto annularly outwardly expanded corrugations or pockets. There is also shown a button end on the brush handle, hereafter more fully explained.

Fig. IX is a fragmentary sectional view of an oval paint brush taken along its horizontal axis and showing in particular the combination of the various elements which make up a practical form of brush and the quick acting reciprocatable sleeve attachment in accordance with this invention.

Fig. X is a cross sectional view taken on the line X—X of Fig. IX.

Fig. XI is a fragmentary sectional view of an oval paint brush but showing the moving type of

wiper and in addition the novel form of pockets for temporarily receiving excess paint on the bristles, as well as the button end on the brush handle.

Fig. XII is a cross sectional view taken on the line XII—XIII of Fig. XI.

Like characters of reference are applied to corresponding parts in all several views.

In the embodiment of my invention as shown by Figs. I to XII inclusive, the numeral 1 designates the bristle pack, preferably oval in shape, and 2 the combination ferrule and guide piece, while 3 is the conventionally rounded tapered handle but having an oval shaped shank 4, the three pieces joined together to form the oval sash brush 5. The ferrule 2 is oval in section throughout its length, rather than oval at its bristle end only and tapered to round at the handle end to receive a round handle as ordinarily constructed. This oval cross section throughout its length, allows the oval shaped quick acting, reciprocatable sleeve 6 with its handle 7 to fit snugly and to slide completely over it as a guide piece. This same oval cross section is maintained in the shank 4 and functions in part as an extension to the ferrule 2 and while this is desirable it is not essential except for that portion actually entering the ferrule 2. Should the shank 4 be made round, then its greatest diameter must at no point be greater than the smallest diameter of the sleeve 6 in order that the latter may be passed over it. The ferrule 2 is preferably made of metal while the shank 4 with the handle 3 is made of wood or moulded from a plastic material.

In the particular form of my invention as shown in Figures I and II the removable stop pin 8 is provided. This pin 8 is so positioned in the shank 4 that the back travel of the sleeve 6 is stopped just after the bristle pack 1 is completely uncovered. For purposes of cleaning, the pin 8 is quickly removed, the sleeve 6 withdrawn over the handle 3, and when assembling the sleeve 6 is slipped over the handle 3 onto the shank 4 and guide piece 2 and the stop pin 8 positioned in the shank 4 avoiding the possibility of the least damage to the bristle pack.

In the modification of my invention as shown in Figures III and IV, I have incorporated in the shank 4 in close proximity to the ferrule 2, the wiper 9 made of a yieldable material, such as felt or a synthetic rubber which is not affected by oils commonly found in paint as is rubber made of latex. My brush when used for the purpose intended requires frequent change of position of the sleeve 2. Paint, under this action, even though the sleeve 6 fits snugly on the guide piece 2, soon works its way back to the shank 4 and handle 3 with its resultant annoyances. The wiper 9, which is fitted snugly in the rectangular groove 10 encircling the shank 4, has a slightly greater perimeter than that inside the sleeve 6. This puts the wiper 9 in compression when in place within the sleeve 6. It is obvious that this arrangement effectively stops the spread of the paint to the handle. The compressed wiper 9 also acts as a brake when the reciprocatable sleeve 6 is moved from one position to another, holding the sleeve 6 in the desired place.

Another modification shown in Figs. III and IV is the spring stop 11 permanently fastened to the handle 3 by its brad-like end 12, the stop 11 forms a part of the spring arm 11 and enters the registering hole 14, drilled through the handle 3, when the spring arm 11 is pressed down allowing the removal of the reciprocatable sleeve 6.

Referring now to the form of my invention as shown in Figs. V and VI, the modification consists in attaching the wiper to the reciprocatable sleeve rather than fastening to the handle shank.

5 The preferred location is within the recess of the sleeve grip 7. This grip 7 is shaped into a rectangular rib. Into this combination grip and wiper holder 7 is fastened the preferable pre-formed oval shaped wiper 15. The oval hole cut in this wiper 15 is of a slightly smaller perimeter than the perimeter of the oval shank 4. It is obvious that when the sleeve is threaded over the handle 3 onto the shank 4 and guide piece 2, the wiper 15 will be slightly compressed around the shank 4 and will form an effective seal against the paint spreading to the handle 3. In this construction the wiper 15 moves with the sleeve 6 instead of remaining stationary.

In the above embodiment also is shown another type of spring stop, attached to and moving with the sliding sleeve 6 thereby removing all projecting parts from the handle and its shank 4. As shown a spring 16 is fastened to the reciprocable sleeve 6 at the point 17. This spring 16 is shaped to be passed through the hole 18 of the sleeve 6 in close proximity to the sleeve grip 7, its free end or shoe 19 is bent so as to approximately parallel the spring arm 16 and just clears the wiper 15. The shank 4 is grooved to just receive the shoe 19 with the deeper recess at the ends thereof to form the vertical shoulders 20 and 21. It is obvious that these shoulders 20 and 21 limit the travel of the sleeve 6 by acting as stops to the shoe 19. The spring set is such as to always exert a downward pressure on the groove 22. When the sleeve 6 is moved over the bristle pack 1 to expose but a very small amount of the bristle pack it is stopped by the shoe 19 contacting the shoulder 20 and when the sleeve 6 is moved in the reverse direction the sleeve 19 contacts the shoulder 21 just as the bristle pack is completely uncovered. While the principal objective of the spring arm 16 functions to limit the travel of the reciprocatable sleeve 6, its downward pressure on its groove 22 assists in holding the sleeve 6 in any set position. The face 23 of the oval shank 4 is so proportioned as to give a sufficient opening for the shoe 19 to clear the shoulder 22 when the spring arm 16 is raised to the inner wall of the sleeve 6. This allows the quick withdrawal of the sleeve 6 from the shank 4 and off the handle 3 for cleaning purposes. When replacing the reciprocatable sleeve 6 the shoe 19 will automatically ride up the handle 3, then across the face 23, and snap down in place in the groove 22 as it clears the shoulder 21.

In the form of my invention as shown in Fig. VII the modification consists in forming a flare or guard 24 at that end of the sleeve 6 which moves over the bristle pack 1. This guard 24 serves to prevent any excess paint on the exterior of the bristle pack 1, from riding up and over onto the exterior side of the sleeve 6 as it is pushed down over the bristle pack and later spreading along the sleeve 6 to the grip 7 with its consequent annoyances.

Referring now to the form of my invention as shown in Fig. VIII, the modification consists in including with the reciprocatable sleeve 6 what I choose to call paint storage pockets. I find that when the sleeve is of an open construction, the motion of the bristles, as the user moves the brush back and forth over the work, causes any

excess paint to press through the openings with its obvious annoyances. I have taken advantage of this effect and find by forming in the reciprocatable sleeve 6, a pocket in the form of one or more annular outwardly extended corrugations or ribs 25 or their equivalent, that these pockets 25 fill with paint when the bristle pack 1 is holding an excess thereof, and empty again as the paint is used up on the work. This assists in preventing brush drip, gives the brush greater paint holding capacity, especially when the sleeve 6 is positioned for a short bristle exposure as is required for example when the brush is used for painting the putty strip of a window frame.

I also find that when the user of my combination brush and quick acting reciprocatable sleeve has but one hand available to make the desired adjustment, that the sleeve 6 may be more easily withdrawn from the bristle pack 1 by pressing the handle end against his body. If wearing light clothing the pointed end of the standard handle tends to penetrate through the clothing. I have therefore modified my invention by shaping the end of the handle 3 with a blunt cap 26 as shown, the diameter of which is less than the smallest diameter of the reciprocatable sleeve 6, which allows the reciprocatable sleeve 6 to pass over it when removing or replacing it on the brush.

In the embodiment of my invention as given in Figs. IX and X, I have shown a combination of elements, which embody desirable features described and illustrated previously, in which the oval sash tool or brush 5 formed of the bristle pack 1, fastened in the unique combination ferrule and guide piece 2, the handle 3 with its oval shank 4 having formed therein the recess 22 with its vertical shoulders 20 and 21 with the face 23 so proportioned that ample clearance is given to the shoe 19 of the spring stop 16, for the quick acting reciprocatable sleeve 6 fitting snugly on and around its guide piece 2 to be withdrawn over the handle 3. The spring stop arm 16 soldered to the metal sleeve 6 passes through the hole 18 of the sleeve 6 and forms the shoe 19 to engage one of the vertical shoulders 20 or 21 and stop further travel of the reciprocable sleeve 6. Formed in the shank 4 is the circumscribed rectangular groove 10 around which is snugly fitted and fastened the felt wiper 9 of sufficient thickness to press slightly against the oval shaped sleeve 6. The end of the sleeve 6 covering the bristle pack 1 is flared to form the guard 24 while the end thereof nearest the brush handle 3 is expanded to form a handle or grip 7 used to move the sleeve backward or forward.

In the embodiment of my invention shown in Figs. XI and XII, I have used the combination of elements described and illustrated previously but have replaced the stationary wiper circumscribing the handle shank with the wiper 15 fitted and held in the sleeve grip 7. The paint pockets 25 are modified in shape from those shown in Fig. 8 to form vertical shoulders 21 in place of the rounded corrugations. The flat or button end 26 of the brush handle 3, illustrated and described in connection with Fig. VIII is also embodied in this combination.

While the foregoing descriptions have made reference to an oval sash tool, a paint brush with the bristle pack oval in section, it will be

readily apparent it is equally applicable to brushes which are round or flat and furthermore is useful for application of materials other than paint.

- 5 Hence I do not desire to limit my invention to the precise details of construction and arrangement of parts hereinbefore set forth, as it is obvious various changes of form and modification for particular purposes may be effected
10 without departing from the essential features of said invention as defined by the following claims.
- Having thus described my invention, I claim:
1. The combination with a paint brush having bristles, a handle, and a ferrule for holding the bristles, of a sliding girdle mounted to embrace and contact with the bristles, and a wiper to prevent the spread of paint to the handle by the sliding girdle.
  - 20 2. The combination with a paint brush having bristles, a handle, and a ferrule preferably made of metal, of a sliding girdle, a spring arm fastened thereto and pressing against a recess provided in the brush handle, and shoulders formed at the ends of the recess to limit the distance of travel of the sliding girdle.
  - 25 3. The combination with a paint brush having bristles, a ferrule for holding the bristles, having the same diametric dimensions throughout its length, and a handle, having a shank of the same diametric dimensions throughout its length and recessed to form shoulders at the ends thereof, of a sliding girdle, having a hand grip at one end, and a flaring guard at the opposite end, a spring attached to the girdle, one end being free and pressing against the recess in the handle shank, and limiting the travel of the sliding girdle by engaging either one or the other of the shoulders formed by the recess, a wiper, preferable of felt, fixed to and positioned around the handle shank in proximity to the ferrule.
  - 30 4. In a paint brush the combination of a bristle pack, a conventional paint brush handle having at one end a shank portion from the end of which the bristle pack projects, said shank portion being of substantially uniform cross section throughout its length and exceeding in cross sectional area the area of the cross section of all parts of the other end portion of the handle and the normal cross sectional area of the bristle pack, and a one piece inelastic girdle of uniform bore conforming in cross section to the cross section of the shank and separable therefrom and slidably mounted thereon for endwise movement, whereby the girdle can be applied to the shank from the end of the handle opposite the bristle pack and can be positioned to cover a portion of the bristle pack without compressing it, the portion of the wall of the girdle positionable over the bristles being imperforate.
  - 45 5. The combination with a pain brush having bristles, a bristle holding ferrule of substantially the same cross sectional area throughout its length and an elongated tapered handle portion having a shank, of a sliding girdle detachable from the rest of the structure and which may be placed in position on the ferrule by sliding it over the end of the shank onto the ferrule, the portion of the wall of the girdle positionable over the bristles being imperforate.
  - 50 6. The combination with a paint brush having bristles, a bristle holding ferrule of substantially the same cross sectional area throughout its length and an elongated tapered handle portion having a shank, of a sliding girdle detachable from the rest of the structure and which may be placed in position on the ferrule by sliding it over the end of the shank onto the ferrule, the portion of the wall of the girdle positionable over the bristles being imperforate.
  - 55 7. The combination with a paint brush having bristles, a bristle holding ferrule of substantially the same cross sectional area throughout its length and an elongated tapered handle portion having a shank, of a sliding girdle detachable from the rest of the structure and which may be placed in position on the ferrule by sliding it over the end of the shank onto the ferrule, the portion of the wall of the girdle positionable over the bristles being imperforate.
  - 60 8. The combination with a paint brush having bristles, a bristle holding ferrule of substantially the same cross sectional area throughout its length and an elongated tapered handle portion having a shank, of a sliding girdle detachable from the rest of the structure and which may be placed in position on the ferrule by sliding it over the end of the shank onto the ferrule, the portion of the wall of the girdle positionable over the bristles being imperforate.
  - 65 9. The combination with a paint brush having bristles, a bristle holding ferrule of substantially the same cross sectional area throughout its length and an elongated tapered handle portion having a shank, of a sliding girdle detachable from the rest of the structure and which may be placed in position on the ferrule by sliding it over the end of the shank onto the ferrule, the portion of the wall of the girdle positionable over the bristles being imperforate.
  - 70 10. The combination with a paint brush having bristles, a bristle holding ferrule of substantially the same cross sectional area throughout its length and an elongated tapered handle portion having a shank, of a sliding girdle detachable from the rest of the structure and which may be placed in position on the ferrule by sliding it over the end of the shank onto the ferrule, the portion of the wall of the girdle positionable over the bristles being imperforate.

HARRY A. RISHEL.
